UNITED STATES PATENT OFFICE.

SETH H. LEAVENWORTH, OF CINCINNATI, OHIO.

CANDLE-RECEIVING RACK.

SPECIFICATION forming part of Letters Patent No. 790,845, dated May 23, 1905.

Application filed September 19, 1904. Serial No. 224,956.

To all whom it may concern:

Be it known that I, SETH H. LEAVENWORTH, a citizen of the United States, residing at Cincinnati, in the county of Hamilton and State 5 of Ohio, have invented new and useful Improvements in Candle-Receiving Racks, of which the following is a specification.

My invention relates to improvements in candle-receiving racks as used upon continuous-wicking candle-molding machinery; and the objects of my improvements are, first, to securely lock the candles in the receiving-rack and, second, to provide a means of adjustment whereby the relative position of the locking-board and the guide-boards can be accurately adjusted. I attain these objects by the mechanism illustrated in the accompanying drawings, in which—

Figure 1 is a perspective view of a portion 20 of a candle-receiving rack. Fig. 2 is a horizontal section on the line, 1 2 Fig. 1. Fig. 3 is a modification of the adjusting-screws F F.

Similar letters refer to similar parts throughout the several views.

25 The guide-boards M M', Fig. 1, are attached to and supported by the housing H, Fig. 1. Below the guide-boards M M' is shown the locking-board A, Fig. 1, this board being free to move laterally within the limits prescribed 30 by the guides L L, Fig. 1. The three previously-mentioned boards are pierced with holes to receive the candles after they have been ejected from the molds in which they are cast.

35 The function of the locking-board A, Fig. 1, is to prevent the candles from dropping back into the candle-mold after the expressing mechanism has been withdrawn, which function is accomplished by moving the locking-board, thus throwing the holes in the locking-board out of alignment with the holes in the receiving-boards. The movement of the locking-board A, Fig. 1, is accomplished by rotating the eccentric E between the guides L L, the 45 center of rotation of this eccentric being fixed upon the housing H. To secure and preserve

the exact relative positions, I attach to the locking-board by screws at J J the guide-plate B, Fig. 2, carrying the lug G. The guide-plate B, to which is attached lug G, is secured 50 to the locking-board A by screws at J J J, Fig. 2.

To plate B is attached the adjusting-plate D, which is secured to plate B by the three screws C C C, the openings for these screws 55 being slotted in plate D to permit a lateral movement between plates B and D when the screws C C C are released. Attached to plate B is the lug G, which projects through the opening N in the adjusting-plate D. The opening N in plate D is flanked on either side by the bosses K K, through which are passed the adjusting-screws F F', which engage with lug G on either side.

When the locking-board A is locked, lever 65 R is in the position as shown in Fig. 1, resting against the stop S, Fig. 1, this stop being so placed that when lever R is brought into contact with it the eccentric E has passed the point of its greatest travel, thus securely 70 locking the board A against any lateral strain which may be brought to bear upon it.

The adjustment of the position of locking-board relative to the receiving-boards M M' is secured by means of the screws F F', the 75 recession of screw F and the advance of screw F', or vice versa, imparting a lateral motion to adjusting-plate D and a consequent variation in the relative positions of the locking-board A and the receiving-boards M M'. 80

Fig. 3 shows a modification of the adjusting-screws F F', wherein a single screw is substituted for the screws F F, said screw having a groove at or near the center, said groove engaging with slot in lug G, as shown. 85

What I claim as my invention, and desire to secure by Letters Patent, is—

1. The combination in a candle-receiving rack of a locking-board, a guide-plate carrying an adjusting-plate, all substantially as set 90 forth.

2. The combination in a candle-receiving

rack of a locking-board, a guide-plate, a lug thereon, an adjusting-plate fitted with adjusting-screws engaging with guide-plate lug, all substantially as shown for the purpose described.

3. The combination in a candle-receiving rack of a locking-board, a guide-plate, a lug thereon, an eccentric-actuated adjusting-plate, adjusting-screws engaging said guide-plate,

all substantially as shown for the purpose described.

In testimony whereof I have signed my name to this specification in the presence of two subscribing witnesses.

SETH H. LEAVENWORTH.
